SKI CREEPER

Asa C. Osborn, Weymouth, Mass.

Application March 28, 1934, Serial No. 717,788

7 Claims. (Cl. 208—184)

This invention relates to a creeping device to be detachably secured to a ski, thereby enabling the skier to traverse difficult ascents or descents when it is desired to prevent slipping of the ski 5 upon the traversed surface.

There are many occasions when the skier wishes to establish positive frictional contact between the skis and the snow or iced surface over which he travels. Such is the case in climbing grades or 10 in trail running in hilly or mountainous country. The skier always needs this frictional grip upon the snow when he is returning to the top of a ski run. It is possible for an experienced skier to scale some grades without the assistance of 15 a special device upon the skis, for instance, by means of the herringbone step, the side step, or by traversing a zigzag path. These methods, however, require skill and are exceedingly tiring to the skier and also consume unnecessary time.

20 It is the chief object of the present invention to provide a device which is readily attached to the ski and which provides the necessary frictional engagement with the traversed surface to enable the skier to move about in difficult places 25 when it is desired to prevent slipping of the skis.

A further object of the invention is to provide a creeping device for skis which is light in weight and may be folded into a compact space or supported at the waist by a belt or strap.

30 A further object of the invention is to provide a creeping device which is constructed to establish a maximum of friction with the traversed surface.

A further object of the invention is to provide 35 a creeper which is easily and quickly attached to or detached from the ski.

Other objects and features will more fully appear from the following description in connection with the accompanying drawing and will be particularly pointed out in the claims.

40 In the drawing:

Fig. 1 is a general view in perspective of the device attached to a ski;

Fig. 2 is a general view of the creeper detached 45 from the ski.

Fig. 3 is a detail view of the front fastening device.

Fig. 4 is a cross section on the line 4—4, Fig. 1.

Fig. 5 is an enlarged detail sectional view of 50 the folds formed in the strip.

A preferred form of the invention is shown in the drawing, in which the creeper is illustrated as comprising a strip 1 of sheet material substantially the same width as the ski 2. The strip 55 is adapted to overlie the bottom face of the ski

for a portion of its length, preferably adjacent the point at which the ski boot 3 is fastened. The strip 1 is provided with transverse shoulders 4, which are formed by projections 5 in the strip. The projections 5 may be constructed in any suitable manner, such as by forming a fold in the material of which the strip is made and fastening the fold. 5

As shown herein, the projections consist of a plurality of plaits 6 formed in the strip. The 10 plaits may be fastened by any suitable means, such as stitching or, as shown herein, by a plurality of rivets 7.

The strip 1 is desirably constructed of relatively heavy sheet material, such as leather or 15 heavy fabric. The material should be of sufficient thickness to present when folded a substantially deep shoulder 4. The plaits 6 are formed in the strip symmetrically with respect to each other, and the strip is fastened to the ski with 20 the shoulders 4 facing towards the rear. Any suitable means may be employed to fasten the strip to the ski.

As illustrated herein, the rear end of the strip 25 is provided with a strap 8 which is securely fastened transversely to the end of the strip. A desirable method of fastening the strap to the strip consists in folding the end portion of the strip 1 completely around the central portion of the 30 strap with the extremity 9 of the strip given an additional half turn about the strap. The additional half turn causes the end of the strip to assume a position between the strap and the extremity 10 of the main portion of the strip. The 35 strap and strip are then secured in place by any suitable means, such as the rivets 11, which extend through the various layers of the strip and also of the strap. This structure presents a neat appearance, and in case the strip is made of fabric, the raveling of the extreme end of the 40 strip is prevented. The free ends 12 of the strap are folded upwardly over the top of the ski and are provided with apertures 13.

The ski is provided with a rigid fastening member such as a screw 14 adapted to be engaged by 45 the apertures 13 of the strap to secure the rear end of the strap to the ski.

The front end of the creeper strip is provided 50 with adjustable means for securing the creeper to the ski. In the preferred form of connecting means illustrated herein, the end of the strap 17 is folded backward to present a loop 19 at one side of the creeper strip 1, and the end of the creeper strip 1 is folded around the strap 17 and its overlapping end portion in the manner here- 55

tofore described in respect to the connection of the strap 8 to the strip, and is secured thereto by rivets 18 passing through the strap 17 and the enveloping portion of the creeper strip 1.

5 A buckle 22 is fixedly secured to the strap 17 at a suitable distance from the creeper strip 1. The portion 21 of the strap 17 beyond the buckle has slidably mounted upon it a metal loop 23, which is adapted to engage a suitable rigid fastening member such as a screw 24 mounted in the top 10 of the forward portion of the ski. In fastening the creeper strip to the ski, the end portion 21 of the strap 17 is passed through the loop 19, the loop 23 engaged over the screw 24, and the end portion 21 of the strap brought backwardly through the loop into engagement with the buckle and drawn up to secure the connecting means firmly in place.

The tip end of the strap 21 desirably is folded 20 over and secured in place by a rivet 25 to prevent fraying of the end of the strap and also to provide a thickened portion, which when passed through the buckle will not be easily withdrawn, thereby preventing the loss of the sliding loop 23.

25 The operations necessary to remove the creeper are obvious and are substantially the reverse of the steps required to secure it to the ski.

Other suitable means may be employed to fasten the creeper to the ski.

30 In use, the projections 5 and the shoulders 4 upon the strip engage with the snow or other surface and prevent relative motion between the ski and the traversed surface. It will be noted that the shoulders 4 offer a maximum resistance 35 to the backward motion of the ski, thereby providing efficient traction for the forward motion of the skier. When, however, the ski is brought forward in taking another step, the projection 5 offers relatively little resistance since the run of 40 the strip between the plaits 6 presents no substantial obstruction and the rearwardly facing shoulders 4 offer no resistance to this forward motion. An ideal condition is thereby established which enables the skier to proceed forward with a minimum 45 of effort and lost motion. Furthermore, by the use of this highly efficient device awkward, tiring and many times dangerous falls are avoided.

The rivets 7 are desirably, but not necessarily, situated slightly forward of the centre line of the 50 plaits 6. As a result of this construction, the fold 25 of the plaits is rendered slightly flexible. When the skier moves forward, the resulting backward force on the ski is absorbed to a large extent by the shoulders 4. If the traversed surface is sufficiently 55 soft and yielding, the fold 25 will yield downwardly, as shown in dotted lines in Fig. 5, thereby automatically more firmly interlocking with the surface and thereby providing greater resistance against backward movement of the 60 ski. During the forward motion of the ski, the fold 25 assumes its normal position. More efficiency may be added to the device by constructing the strip 1 of coarsely woven fabric, which provides added friction when the snow is in that 65 condition where it tends to be plastic, in which case the imprint of the fabric creates an additional gripping action therewith.

The rivets used to secure the folds or plaits are

desirably so positioned that their rough upset ends overlie the bottom face of the creeper. The expanded ends of the rivets thereby present an irregular surface having many sharp edges which act to increase the gripping power of the creeper, especially upon an icy surface.

Having thus described the invention, what is claimed as new, and desired to be secured by Letters Patent, is:

1. A ski creeper comprising a strip of sheet 10 material adapted to overlie the bottom face of the ski, a plurality of folds in said strip presenting shoulders to engage the traversed surface and prevent slipping of the ski thereon, means to fasten the folds and means to fasten said strip 15 to the ski.

2. A ski creeper comprising a strip of sheet material adapted to overlie the bottom face of the ski, said strip having a plurality of transverse plaits, means to secure said plaits and 20 means to fasten said strip to the ski.

3. A ski creeper comprising a strip of sheet material adapted to engage the bottom face of the ski, said strip having a plurality of transverse plaits folded symmetrically with respect to 25 each other and presenting shoulders facing in one direction, means to secure said plaits, said shoulders engaging the traversed surface to secure a maximum gripping action of the ski upon the traversed surface in one direction and means 30 to fasten said strip to the ski.

4. In combination with a ski having rigid fastening members thereon, a creeping device comprising a strip of sheet material adapted to overlie the bottom face of the ski, said strip having a 35 plurality of folds, means to secure said folds and fastening means at the ends of said strip coating with the fastening members on the ski to secure the strip in position thereon.

5. In combination with a ski having rigid fastening members thereon, a creeping device comprising a strip of sheet material adapted to overlie the bottom face of the ski, said strip having a plurality of folds, means to secure said folds and adjustable fastening means at the ends of said 45 strip coating with the fastening members on the ski to draw the strip taut and secure it in position upon the ski.

6. A ski creeper comprising a strip of sheet material adapted to engage the bottom face of the ski, said strip having a plurality of transverse plaits, means to secure said plaits, said securing means being disposed adjacent one edge of the plaits thereby permitting flexibility of the double thickness of the sheet material at the 55 other edge of the plait and means to secure said strip to the ski.

7. A ski creeper comprising a strip of sheet material adapted to engage the bottom face of the ski, said strip having a plurality of transverse folds presenting shoulders, a plurality of metallic rivets acting to secure said folds and having their expanded ends at the bottom face of the strip thereby presenting rough metallic areas for gripping icy surfaces and means to secure said 65 strip to the ski.

ASA C. OSBORN.
